ARCHERY BOW SIGHT

Edward J. Zielinski, 1006 Symes Ave., Royal Oak, Mich.
Filed Aug. 3, 1959, Ser. No. 831,229
4 Claims. (Cl. 33—46)

This invention relates to archery bow sights and more particularly pertains to a sight device having an adjustable mounting and movable, adjustable and reversible sight pins for selectively mounting movable sights of different types in multiple.

Bow sights have been employed heretofore to facilitate the sighting of the bow at different ranges through different visual sights means. However, the several devices of the prior art have not proven entirely satisfactory inasmuch as they are unsatisfactory in design and construction, do not provide adequate facility in use, and are not sufficiently adjustable to be suitable for the archer under all conditions.

With the foregoing in view, the primary object of the invention is to provide a bow sight which is adequate in design and construction, highly adjustable and variable, and which provides multiple mounts for multiple bow sights thereby rendering the device completely suitable for the archer under all conditions.

An object of the invention is to provide a bow sight having a lineal slide bar track aligned with the bow and a sliding carriage block adjustably disposed thereon for elevational adjustment relative to the track and bow.

An object of the invention is to provide multiple transverse apertures in the sliding block for supporting sights thereon elevationally adjustable with the block.

An object of the invention is to provide a jam-head in the block having apertures aligned with the block apertures for receiving the sight supporting pins therein for the purpose of binding the pins in their laterally adjusted position.

An object of the invention is to provide a transverse aperture in the block and jam-head for reversibly receiving at the supporting pins therein from either side of the device so as to selectively support the sight on either side of the bow.

An object of the invention is to provide multiple sight supporting means on the slide block for supporting multiple sights on either or both sides of the track and bow.

An object of the invention is to provide a friction spring disposed between the block and slide track for frictionally positioning and holding the block in the adjusted position relative to the slide track.

An object of the invention is to provide an index arm on the sliding block for co-operation with a yardage index scribed on a bow.

An object of the invention is to provide a threaded aperture in the slide block and a threaded sight supporting pin therethrough which is adjustable for axial projection by rotating the threaded pin relative to the threaded block aperture.

These and other objects of the invention will become apparent by reference to the following description of a bow sight embodying the invention taken in connection with the accompanying drawings in which:

FIG. 1 is a side elevational view of the bow sight mounted on a bow.

FIG. 2 is a face elevational view, greatly enlarged, of a section of FIG. 1 showing the integration and structure of the sight.

FIG. 3 is a cross sectional view of FIG. 2 taken on the line 3—3 thereof.

FIG. 4 is a cross sectional view taken on the line 4—4 of FIG. 2.

2

FIG. 5 is a cross sectional view of FIG. 3 taken on the line 5—5 thereof.

FIG. 6 is a perspective view of a section of a bow with an inventive sight device mounted thereon.

FIG. 7 is a cross sectional view of FIG. 6 taken on the line 7—7 thereof; and

FIG. 8 is a perspective view similar to FIG. 6 showing a modified slide bar track.

Referring now to the drawings wherein like numerals refer to like and corresponding parts throughout the several views, the bow sight device disclosed therein to illustrate the invention comprises, a slide bar track 10 mounted on the bow 11, a sliding block 12 mounted on the slide track 10 equipped with an index arm 13 for reading the elevational index scribed on the bow, a sight supporting pin 14 supporting the ball sight 15, and paired sight supporting pins 16 and 17 supporting the cross hair or prism sight 18.

More particularly the archery bow sight device, FIG. 20, has a multiple adjustable and reversible mount comprising the track 10 including a slide bar 20, legs 21 and 22 on either end of the slide bar 20, and a foot 23 and 24 on each respective leg with feet 23 and 24 being attachable to a bow 11 with the legs 21 and 22 spacing the bar 20 from the bow; the bar 20 has front and back faces 25 and 26 and opposite lineal edges 27 and 28. The carriage 12 is slidably mounted on the track 10 and includes, FIGS. 4 and 7, a sliding block 29 having a channel 30 slidably disposed on the bar 20 defined by opposed grooved bottom ways 31 and 32 enveloping the slide bar lineal edges 27 and 28 with the leg edges being relieved in the area 33 for by-passing the block ways 31 and 32 in mounting and dismounting the block 29 and the track 10 with the block having a spring containing recess 34 above said channel 30 and a hair-pin type leaf spring 35 disposed in the recess 34 having a first leaf 36, FIG. 3, bearing against the block 29 and a second leaf 37 bearing against the bar 20 frictionally positioning the block 29 relative to the bar 20 in any lineally adjusted position; the spring leaves 36 and 37 are interconnected by a loop portion 38 outside said block 29 area; a pin 39, FIG. 5, is disposed through the block 29 abutting the first spring leaf 36 confining it laterally against the block 29 which first spring leaf 36 has projections 40 and 41 on either side of the pin 39 preventing lineal movement of the spring 36 relative to the block 29 rendering the spring 35 movable with the block 29 relative to the track 10, and at least one set screw 42 in the block 29, FIG. 2, engaging the track bar 20 for mechanically fixing the block 29 on the bar 20 in any adjusted position.

In one embodiment, FIG. 8, one leg 21-A is reversely curved under the bar 20-A to provide added track spring-wise flexing in conjunction with bow bending and to raise one end of the bar higher than the other to compensate for the bow's curvature.

The block 29 has a top 50 opposite the bottom ways 31 and 32, opposite ends, opposite sides above the ways, a central slot 55 leading upwardly through the top 50, FIGS. 2—5, and multiple side to side transverse apertures leading through the block 29 in the area of the slot 55; the jam-head 56 is slidably disposed in the slot 55 and has apertures axially aligned with the block transverse apertures; the sight supporting pins 14, 16, and 17 lie in the block 29 and head 56 aligned apertures; a bolt 60 is fixed on the head 56 leading through the block top 50, and a nut 57 is threaded on the bolt 60 engaging the block top 50 adapted upon tightening to develop draw force on the bolt 60 and the head 56 outwardly of the block top 50 jamming the pins 14, 16, and 17 between the block 29 and head 56 fixing the pins rela-

tive thereto; the pins being sidewise extensably adjustable relative to the block by loosening the nut.

Preferably, the head 56 has at least one threaded aperture 14-A, FIG. 4, with the pin 14 disposed therein being matingly threaded and extensably adjustable relative to the block 29 by loosening the nut 57 and rotating the pin 14 relative to the head 56, and also preferably, the block 29 and head 56 have at least two paired spaced aligned apertures with the paired spaced pins 16 and 17 lying in the apertures with the visual sight means 18 interconnecting the pins 16 and 17 exteriorly of the block 29 with the paired interconnected pins firmly supporting the sight means. The curved index arm 13 on the block 29 leads sidewise outwardly therefrom so as to project beyond a bow 11 on which the device is mounted with the arm 13 having a downwardly curving end depending below the track 10 so as to overlie the side of a bow 11 on which the device is mounted so as to be accurately readably relative to elevation index markings, not shown, scribed on a bow.

Preferably the block top 50 has paired side to side surface grooves 61 and 62 and a plate 63 overlying the block top 50 under the nut 57 with the plate 63 having side to side surface grooves 64 and 65 opposite the block top grooves 61 and 62 forming a channel in conjunction therewith; the sight means supporting pins, not shown for clarity, disposed in the channel with the block and plate under the draw force of the nut and bolt binding the pins in the channels in adjusted position.

The device is easily mounted on a bow 11 by fixing the track 10 thereon via the screws 70 and 71, FIGS. 6 and 8, and the carriage 12 is then easily mountable on the bar 20 by sliding the ways 31 and 32 through the recessed or reduced portion 33 of the legs 21 or 21-A whereupon the spring 35 is compressed under torsion frictionally engaging the block 29 on the slide bar 20 portion of the track.

In operation, the archer loosens the nut 57 permitting the apertures of the head 56 and the block 29 to align whereupon he selectively inserts the pins 16 and 17 from either side of the block so as to position the sighting prism or cross hairs 18 on either side of the block and he then screws the ball sight 15 pin 14 into the head 56 threaded apertures 14-A from the other side of the device opposite to the sight 18 whereupon the device is positioned as desired. He then moves the pins 16 and 17 and the pin 14 inwardly and outwardly sidewardly of the bow until the desired location is obtained whereupon by tightening the nut 57 the sight supporting pins 14, 16, and 17 are locked in the desired position. The archer then moves the carriage block 29 upwardly and downwardly on the slide bar 20 until the proper sight is obtained or moves the index arm 13 relative to index marks of the bow to the desired elevational position whereupon the slide block is held under the torsion of the spring 35 and/or by tightening the set screws 42 as desired. In the event a plate 63 is employed it is to be noted that the plate has surrounding apertures not in engagement with the set screws 42, for insertion of a screw driver therethrough to render the set screws 42 turnable. Similar or the same sight supporting pins 16 and 17 are also inserted in the channels between the plate 63 and the block top 50 as formed by the grooves 61, 62, 64, and 65 it is obvious that by tightening the nut 57 that the plate 63 is jammed downwardly against the block locking the pins 16 and 17 in the channels formed by the opposed grooves.

While the pins 16 and 17 have been shown interconnected, it is obvious that they can be separately disposed and independently support different sighting devices and that the device can support several and/or multiple sets of individual pins at desired locations for the purpose of supporting visual sights suitable to the multiple and hard to satisfy demands of an expert archer.

Although but a few embodiments have been shown

and described in detail, it is obvious that many changes may be made in the size, shape, detail, and arrangement of the various elements of the invention within the scope of the appended claims.

5 I claim:

1. An archery bow sight device having multiple adjustable and reversable mounts comprising a track including a slide bar, legs on either end of said slide bar, and a foot on each said leg; said feet being attachable to a bow with said legs spacing said bar from the bow; said bar having front and back faces and opposite lineal edges; a carriage slidably mounted on said track including a sliding block having a channel slidably disposed on said bar defined by opposed grooved bottom ways enveloping said slide bar lineal edges; said track leg edges being relieved in one area for by-passing said block ways in mounting and dismounting said block on said track; said block having a spring containing recess 10 above said channel; a hair-pin type leaf spring disposed 15 in said block recess having a first leaf bearing against said block and a second leaf bearing against said bar frictionally positioning said block relative to said bar in any movably adjusted position; said spring leaves being interconnected by a loop portion outside said block 20 area; a pin disposed through said block abutting said first spring leaf confining it laterally against said block; said first spring leaf having projections on either side of said pin preventing lineal movement of said spring relative to said block; said spring being movable with 25 in said block relative to said track; at least one set screw 30 in said block engaging said track bar for mechanically fixing said block on said bar in any adjusted position; said block having a top opposite said bottom ways, opposed ends and opposed sides above said ways, a central 35 slot leading upwardly through said top, and at least one side to side transverse aperture leading through said block in the area of said slot; a jam-head slidably disposed in said slot having at least one aperture axially aligned with said block transverse aperture, at least one sight 40 supporting pin lying in said block and head aligned apertures; a bolt on said head leading through the top of said block; a nut on said bolt engaging said block top adapted upon tightening to develop draw force on said bolt and head outwardly of said block top jamming said pin between said head and said block fixing said pin relative thereto; said pin being slidably extensably 45 adjustable relative to said block by loosening said nut; and a curved index arm on said block leading sidewise outwardly therefrom so as to project beyond a bow on which the device is mounted; said arm having a downwardly curving end depending below said track so as to overlie the side of a bow on which the device is mounted so as to be accurately readable relative to index markings scribed on a bow.

55 2. An archery bow sight device having multiple adjustable and reversable mounts comprising a track including a slide bar, legs on either end of said slide bar, and a foot on each said leg; said feet being attachable to a bow with said legs spacing said bar from the bow; said bar having front and back faces and opposite lineal edges; a carriage slidably mounted on said track including a sliding block having a channel slidably disposed on said bar defined by opposed grooved bottom ways enveloping said slide bar lineal edges; said track leg edges being relieved in one area for by-passing said block ways in mounting and 60 dismounting said block on said track; said block having a spring containing recess above said channel; a hair-pin type leaf spring disposed in said block recess having a first leaf bearing against said block and a second leaf bearing against said bar frictionally positioning said block 65 relative to said bar in any movably adjusted position; said spring leaves being interconnected by a loop portion outside said block area; a pin disposed through said block abutting said first spring leaf confining it laterally against said block; said first spring leaf having projections on 70 said block; said first spring leaf having projections on 75

either side of said pin preventing lineal movement of said spring relative to said block; said spring being movable with said block relative to said track; at least one set screw in said block engaging said track bar for mechanically fixing said block on said bar in any adjusted position; said block having a top opposite said bottom ways, opposed ends and opposed sides above said ways, a central slot leading upwardly through said top, and at least one side to side transverse aperture leading through said block in the area of said slot; a jamhead slidably disposed in said slot having at least one aperture axially aligned with said block transverse aperture, at least one sight supporting pin lying in said block and head aligned apertures; a bolt on said head leading through the top of said block, a nut on said bolt engaging said block top adapted upon tightening to develop draw force on said bolt and head outwardly of said block top jamming said pin between said head and said block fixing said pin relative thereto; said pin being slidably extensibly adjustable relative to said block by loosening said nut; and said block top having at least one side to side surface groove; a plate overlying said block top under said nut having a side to side surface groove opposite said block top groove forming a channel in conjunction therewith, and a sight means supporting pin disposed in said channel; said block and plate under the draw force of said nut and bolt binding said pin in said channel in adjusted position.

3. An archery bow sight device having multiple adjustable and reversible mounts comprising a track including a slide bar attachable to a bow; said bar having opposite front and back faces and opposite lineal edges; a carriage slidably mounted on said track bar including a sliding block having a channel slidably disposed on said bar defined by opposed grooved bottom ways enveloping said slide bar lineal edges; said block having a spring containing recess above said channel; a spring disposed in said block recess bearing against said block and against said bar frictionally positioning said block relative to said bar in any movably adjusted position; said spring being movable with said block relative to said track; said block having a top opposite said bottom ways, opposed ends and opposed sides above said ways, a central slot leading upwardly through said top; and at least one side to side transverse aperture leading through said block in the area of said slot; a jam head slidably disposed in said slot having at least one aperture axially aligned with said block transverse aperture, at least one sight supporting pin lying in said block and head aligned apertures; a bolt on said head leading through the top of said block, a nut on said bolt engaging said block top adapted upon tightening to develop draw force on said bolt and head outwardly of said block top jamming said pin between said head and said block fixing said pin relative thereto; said pin being slidably extensibly adjustable relative to said block by loosening said nut; and a curved index arm on said block leading sidewise outwardly therefrom so as to project beyond a bow on which the device is mounted; said arm having a downwardly curving end depending

below said track so as to overlie the side of a bow on which the device is mounted so as to be accurately readable relative to index markings scribed on a bow.

4. An archery bow sight device having multiple adjustable and reversible mounts comprising a track including a slide bar attachable to a bow; said bar having opposite front and back faces and opposite lineal edges; a carriage slidably mounted on said track bar including a sliding block having a channel slidably disposed on said bar defined by opposed grooved bottom ways enveloping said slide bar lineal edges; said block having a spring containing recess above said channel; a spring disposed in said block recess bearing against said block and against said bar frictionally positioning said block relative to said bar in any movably adjusted position; said spring being movable with said block relative to said track; said block having a top opposite said bottom ways, opposed ends and opposed sides above said ways, a central slot leading upwardly through said top; and at least one side to side transverse aperture leading through said block in the area of said slot; a jam head slidably disposed in said slot having at least one aperture axially aligned with said block transverse aperture, at least one sight supporting pin lying in said block and head aligned apertures; a bolt on said head leading through the top of said block, a nut on said bolt engaging said block top adapted upon tightening to develop draw force on said bolt and head outwardly of said block top jamming said pin between said head and said block fixing said pin relative thereto; said pin being slidably extensibly adjustable relative to said block by loosening said nut; said block top having at least one side to side surface groove; a plate overlying said block top under said nut having a side to side surface groove opposite said block top groove forming a channel in conjunction therewith, and a sight means supporting pin disposed in said channel; said block and plate under the draw force of said nut and bolt binding said pin in said channel in adjusted position.
